CLAIM

The ornamental design for a “smoothing tool for use in forming concrete structures,” as shown and described.

DESCRIPTION

FIG. 1 is a perspective view of a smoothing tool for use in forming concrete structures, showing my new design;

FIG. 2 is a front elevational view thereof;

FIG. 3 is a rear elevational view thereof;

FIG. 4 is a left side elevational view thereof

FIG. 5 is a right side elevational view thereof;

FIG. 6 is a top plan view thereof; and,

FIG. 7 is a bottom plan view thereof.
